COLLAPSIBLE BOX

Samuel Hoffman, South Orange, N. J.

Application August 17, 1934, Serial No. 740,271

2 Claims. (Cl. 220—6)

My invention relates to improvements in collapsible boxes.

An object of my invention is to provide a convenient device of the character specified, which is particularly adapted for use in the delivery of merchandise from the retail shopkeeper to the consumer where it is desirable to provide a receptacle which may be stacked in a delivery truck for convenient handling, and folded or collapsed for storing.

A further object of my invention is to provide a light, strong and durable collapsible box. A further object of my invention is to provide means whereby boxes of the character specified may be conveniently and securely stacked.

A preferred embodiment of my invention is illustrated in the accompanying drawing, in which Figure 1 is a perspective view of the device,

Figure 2 is a plan view of the same,

Figure 3 is a section on the line 3—3 in Fig. 2 and

Figure 4 is a view of the box folded or collapsed.

Similar characters of reference refer to similar parts throughout the several views.

My improved box comprises two hinged side panels 1 and 2, two end panels 3 and 4, a bottom panel 5, hinged to one of the side panels, and a pair of handle members 6 and 7, the ends of which form dowels for the corner hinges as hereinafter described.

The adjacent marginal edge sections of the panels 1, 2, 3 and 4 are cut out at intervals and bent or rolled inwardly to form spaced tubular marginal beads 8, 9, 10 and 11 which intermesh and form wing sockets for the legs or dowels 12, 13, 14 and 15 of the handle members 6 and 7 respectively.

The lower marginal edge section 16 of the panel 2 is cut out at intervals and bent or rolled inwardly to form spaced tubular marginal wing beads 17 and like tubular marginal beads 18 are formed on the adjacent marginal edge of the bottom panel 5 which said tubular beads intermesh to form a tubular socket for the shaft or dowel 19.

The free edge section 20 of the bottom panel 5 is bent to form a hook section which rests upon the inwardly bent marginal edge 21 of the side panel 1.

The bottom panel 5 is shorter than the side panels 1 and 2 and is spaced from the end panels 3 and 4, thereby forming seats 22, 23 between the short ends of the bottom panel 5 and the end

panels 3 and 4 of the box, which are adapted to receive the bails or handles 6 and 7 of the box below when two or more counterpart boxes are stacked one above the other.

The free marginal edges 24, 25, 26 and 27 of the panels 1, 2, 3 and 4 may be rolled over to form stiffening beads.

The bottom panel 5 is thus hinged, as above described, to the side panel 2 and swings on its hinge, and when lowered to its normal position 10 for use, the free edge of the bottom panel 5 rests upon the marginal bead of the opposite panel 1 and, when so positioned, the box is held thereby in its open operative position and the box may then be carried by the handles or bails 6 and 7. 15

When a plurality of said boxes are stacked one above the other, the handle 6 and 7 of the lower box enters the seats 22, 23 of the upper box, thus holding the stack against accidental displacement but permitting the stack to be easily taken down 20 and the upper box of the stack removed.

When it is desired to collapse the box for storing or the like, the bottom panel 5 is raised on its hinge into parallel relation with the side 2 and the panels 1, 2, 3 and 4 are folded on their respective hinges.

I prefer to form the handles 6 and 7 of wire or the like and to so position them that when they enter the said seats 22, 23 in a box above, they will lie close against the end panels 3 and 4 of the said upper box so that the contents of such upper box may not be disturbed thereby.

Having thus described my invention, what I claim is:

1. A collapsible box comprising in combination two side panels, two end panels, hinges connecting the said panels, a bottom panel hinged to one of the said side panels and spaced at its respective ends from the said end panels to form seats for the handles of a box below, and a pair of handle members having legs which form dowels for the said hinges on the side panels and end panels.

2. A collapsible box comprising in combination two side panels, tubular marginal wing beads thereon, two end panels, tubular marginal wing beads on said end panels and intermeshing with the said first named beads, dowels in said tubular beads and extending above the said panels to form handles, and a bottom panel hinged to one of the said side panels and spaced from the end panels to form seats for the handles of a box below the same.

SAMUEL HOFFMAN.
